UNITED STATES PATENT OFFICE

ARCHIBALD D. COWAN, OF FULTON, ILLINOIS, ASSIGNOR TO PATENT NOVELTY COMPANY, OF FULTON, ILLINOIS, A CORPORATION OF ILLINOIS

DESIGN FOR A TOY WHISTLING CLOWN

Application filed January 13, 1930. Serial No. 34,123. Term of patent 3½ years.

To all whom it may concern:

Be it known that I, ARCHIBALD D. COWAN, a citizen of the United States, and resident of Fulton, in the county of Whiteside and State of Illinois, have invented a new, original, and ornamental Design for a Toy Whistling Clown, of which the following is a specification, reference being had to the accompanying drawing, forming a part thereof:

Figure 3 is the other side of said toy.

I claim:

The ornamental design for a toy whistling clown, as shown.

ARCHIBALD D. COWAN.
